1

The subject of the present invention is an electric cut-out designed to break an electric circuit when the value of the current exceeds a determined nominal value. A small excess of current causes it to operate. A dead short-circuit even repeated several times and involving considerable overloads causes its operation without harm to its parts.

This cut-out is adapted more particularly for the protection of small power motors, domestic power and lighting installations, electric equipment of vehicles, and in general any electric circuits where a small excess current as well as a short-circuit may involve damage or accident.

In the cut-out according to the invention, a moving contact is carried by a flexible blade held in the set, circuit making position by engagement with a latch blade rockable on a push rod and acted upon by a spring which holds it engaged with the flexible blade, the push rod being itself held in its corresponding inward position by a pawl under spring action, operation of the cut-out being caused by deflection of a bimetallic strip in series with the controlled circuit, which presses the latch blade into a housing in the push rod, so releasing the flexible blade which, being suddenly retracted, opens the circuit and strikes the tail end of the pawl thereby releasing the push rod which a spring pushes into its outer, released position, the rocking blade at the same time re-engaging the flexible blade. This re-engagement enables the cut-out to be reset by depressing the push rod which is re-engaged by the pawl, while the flexible blade is returned to contact making position.

A release button can be provided which acts upon a lever to rock it, the lever either acting on the tail end of the pawl or pushing the rocking blade into its housing.

The accompanying diagrammatic drawings show by way of example, some embodiments of the invention.

Figures 1 and 2 are vertical sections of the cut-out in set position, taken respectively on the line 1—1 of Figure 2 and 2—2 of Figure 1.

Figure 3 is a vertical section on the line 1—1 of Figure 2, but with the cut-out after operation, i.e. with the circuit opened.

Figures 4 and 5 are detail vertical sections of a modification of the contacts, shown respectively open, on the line 4—4 of Figure 5 and closed, on the line 5—5 of Figure 4.

Figures 6 and 7 are similar views of another modification of the contacts shown respectively

2

open, on the line 6—6 of Figure 7, and closed, on the line 7—7 of Figure 6.

Figure 8 is an elevation of one form of the bimetallic strip.

5 Figure 9 shows the strip in side view in normal condition and also flexed.

Figures 10 to 12 are vertical sections of the cut-out, in set position, provided with another form of release, taken respectively on the line 10—10 of Figure 11, the line 11—11 of Figure 10 and the line 12—12 of Figure 10.

Figures 13 and 14 are views of another form of the bimetallic strip, shown respectively in elevation and formed into a helix.

15 15 The cut-out comprises a base 2 of insulating material supporting the mechanism which is protected by a hood 3 also of insulating material. This hood is fixed on the base by screws 4. The main frame 5, reinforced by a web 6 supports the parts associated with the moving contact 15 and a terminal 7 screwed into an angle bracket 8 (Figure 3), the terminal and bracket both being insulated electrically from the frame 5.

15 25 A bifurcated bimetallic strip 9 controlling the operation of the cut-out is secured by screws 11 to the frame 5 to which is electrically connected one of its limbs while the other limb, insulated from the frame is connected to the angle-bracket 8, that is to the terminal 7. At its end the bimetallic strip carries an insulated knob 12 abutting against a latch blade 13.

35 30 One end of a blade 14 is anchored to the frame 5 by a spring 16 consisting of several leaves of small thickness which afford it greater flexibility and robustness. To its other end is secured a spring tongue 17 carrying the moving contact 15. A latch roller 18 pivots on a spindle pressed in the blade 14 (Fig. 2).

40 40 A push rod 19, for example of rectangular section, slides in the upper part of the frame 5 and is guided at its lower end by a guide 20 fixed to the base of the frame 5.

45 45 The latch blade 13 is pivoted by its upper end 22 to the rod or pillar 19 at 21 in a groove 23 in which it is housed, a spring 24 urging it out of the housing groove so that it retains the blade 14 when the cut-out is set by engagement of the roller 18 in a notch 31 of blade 13.

50 50 When the cut-out is set, a pawl 26 urged by a spring 25 engages a notch in the push rod 19 and so holds the latter in its innermost position; the push rod 19 terminates in a setting press-button 27.

55 55 A release button 23 subjected to a return spring 29, can act upon the end of a lever 31 pivoted on

the same pin 30 as the pawl 26, the other end of the lever 31 being positioned to co-act with the tail of the pawl.

The second terminal 32 holds to the base 2 (Figure 1) a block 33 of insulating material about which is a winding 34. A magnetic core 35 passes through the block 33 and carries the fixed contact 36. One end of the winding 34 is connected to the terminal 32 and its other end to the contact 36 through the magnetic core 35.

The terminals 7 and 32 can be in the form of slotted pins as shown in Figures 1 and 3, of standard diameter and spacing, or in the form of spring contacts, or of any other form adapted to carry the current.

The operation of the cut-out is as follows:

When it is set (Figures 1 and 2), the current entering for instance at terminal 7 passes through the angle bracket 8, then in succession through the two limbs of the strip 9, the spring 16, the blade 14, the moving contact 15, the fixed contact 36, the winding 34 and the second terminal 32.

The cross-section of the two limbs of the strip is made such that it can carry the nominal current without noticeable deflection. When the current rises above predetermined value, the strip deflects under the heating effect and its end 9a, through the insulated knob 12 pushes the latch blade 13 into the housing in the push rod 19 (Figure 2).

The roller 18 leaves the notch 37 of the blade 13 and, the blade 14 being released, immediately obeys its spring 16, so violently withdrawing the moving contact 15 from the fixed contact 36.

The upper end of the contact 15 then strikes the tail end of the pawl 26, which accordingly releases the push rod 19.

The spring 38 encircling the guide 20 raises the push rod which assures its released position (Figure 3). In this position the roller 18 on the blade 14 lodges again in the notch 37 in the blade 13.

In this illustrated form of construction of the cut-out, the button 28 enables the cut-out to be operated without application to it of an excessive current. The button 28 acts on the end of the lever 31 which rocks and with its other end disengages the pawl 26 from the push rod 19 which is pushed outward by its spring 38, so releasing the blade 14 carrying the moving contact 15.

To re-set the cut-out it is only necessary fully to depress the button 27, thus depressing the blade 14 through the agency of the latch blade 13, and loading the spring 16 and the spring 38 encircling the guide 20. The pawl 26 under the action of its spring 25 locks the push rod 19 in its innermost position and the cut-out is again in its set position (circuit closed).

The bent form of the blade 14 enables the axis of the roller 18 to be exactly perpendicular to the edge of the notch 37 in the blade 13. This important condition ensures reliable operation of the roller without lateral friction.

According to the nominal current, the contacts can be constructed in various ways to ensure maximum effectiveness and minimum wear of the device.

Figures 1 to 3 show a type of contact suitable for very low currents. In this case, the bimetallic strip, necessarily of small section would be rapidly damaged by the heavy current resulting from a dead short circuit, if no special provision were made.

The winding 34 in series with the strip 9 has a two-fold purpose;

a. It is constituted by a wire of high resistivity and high melting point, of heavy enough section not to have noticeable resistance when carrying the nominal current. But in the case of a short circuit its resistance is sufficient to limit the current. In this way it protects the bimetallic strip until release, which is practically immediate, is completed.

b. It forms the winding of an electromagnet, the magnetic flux of which passing through the contact-carrying core 35, assists in blowing out the arc at break. The contact 36 can be of carbon to avoid welding together of the contacts at break.

Other forms of contact can be provided for higher currents.

Figures 4 and 5 relate to an arrangement of multiple contacts. The multiplication of the contacts reduces the heating effect for the same equivalent total surface and it ensures better maintenance of the surfaces in contact.

Further, the arrangement shown comprises principal contact 41 and 42, 43 and 44, of metal, and auxiliary contacts 45 and 46. The contact 45 of carbon, is movable. This enables the break to take place in two stages.

1. When the blade 14 rises the break takes place in the first stage at the principal, metal contacts 41 and 42, 43 and 44. The contact 45 however, lifted by a spring 47, moves with the movable contact 46 until the contact carrier 48 reaches its highest position. During the very short time during which the contact 45 is moving, the whole of the current passes through it and the metal contacts 41 and 42, 43 and 44 separate without the formation of an arc.

2. When the contact 46 leaves the contact 45, the arc is produced between metal and carbon surfaces, thus avoiding the risk of welding together. The carbon contact 45 is connected to a plate 49 and so to the terminal 32, by a flexible lead 51 providing for the passage of current between these parts.

Figures 6 and 7 show a modification of this arrangement.

The contacts 45 and 46 are identical with and have the same purpose as those described above.

The principal, metallic contacts 52 and 56 instead of being fixed like the contacts 41 and 43, are movable about an axis 53 and rise slightly at break under the action of springs 54 and 55. This rise ensures a slight sliding of the cylindrical surface of the contacts 52 and 56 on the contact 57. This sliding cleans the surfaces of the contacts and the break does not take place at the same points as does the passage of current during service.

It is to be noted that the pressures on the contacts 52 and 56 are equalised because the contact 57 can rock on the rivet 58 which secures it to the blade 14 and the spring 16 tends to push the blade 14 and the contact 57 against the contacts 52 and 56.

In the embodiments which have just been described release effected by pressure on the button 28 does not take place if the button 27 is held depressed.

In that shown in Figures 10 to 12, release is obtained in these circumstances, without loss of the small bulk of the cut-out which enables it to be used on built-in distribution boards.

To this end, the button 28a is returned to its position of rest shown in Figures 10 and 11 by a

spring 59 abutting a support 61 carried by a distance-piece 62. The button also carries a ramp 63 having an inclined profile which as it moves inwards causes a lever 65 pivoted on the distance-piece 62 to rock in the direction of the arrow 64 (Figure 11).

The end 66 of this lever 65 accordingly presses in the direction of the arrow 67 below the pivotal axis 68 of the latch blade 13 (Figure 12) thus pushing the latter into its housing in the push rod 19, the wall of the notch 37 running off the roller 18 to release the blade 14 which rises, so opening the circuit at the contacts of the cut-out.

To obtain a cut-out able to control very low currents, of the order of one ampere or less for example while holding the device within small limits of size, the width and thickness of the limbs of the bimetallic strip must be reduced, because it is the cross-section of this strip which determines the nominal current of the cut-out, but as the fragility of the limbs increases proportionately with the reduction of the cross-section, the mechanical effort of which the strip is capable is also limited accordingly.

To increase substantially both the mechanical effort developed and the actual ohmic resistance, the bimetallic strip 69 (Figures 10, 12 and 14) can be formed into a helix in such a way that a strip is obtained having the same dimension in length as the strip 9 of Figure 1.

The deflection is no longer a bend as shown by Figure 9, but a twist as indicated by the arrow 71 in Figure 14. This possibility of obtaining an increase in the effort exerted by the strip and in its resistance, for a given current enables a cut-out to be constructed releasing at lower currents than in the case of cut-outs of the same bulk having a straight bimetallic strip as shown in Fig. 8.

The operation of the cut-out shown in Figures 10 to 12 is as follows:

The whole current passing through the bimetallic strip causes heating of its turns 72 and when the current exceeds the nominal value, the turns tend to wind tighter to a substantial degree. The free end 73 of the helix accordingly acts on the latch blade 13 which releases the blade 14. For satisfactory operation and to avoid any bending, it is necessary that the turns 72 should bear against the hood 3.

The advantages of the cut-out according to the invention, which is adapted to be used to replace fusible cut-outs are:

1. A very small bulk enabling it to be used on commerical fuse bases, whether of the type with sockets for pins, for spring contacts, or for permanently mounted fuse-holders;

2. A very high sensitivity of operation consequent upon the combination of three features:

(a) Instantaneous heating of the bimetallic controlling strip by the direct transmission of the current through it.

(b) Reduction of the effort necessary for operation by the use of a latch blade in the form of a lever on which the strip acts,

(c) Unlatching effected by the action of a small roller, thus without any sliding friction;

3. Ease of resetting and the tamperproofness of a device actuated by a re-setting press-button easily accessible even if the cut-out is sealed to its base.

The separation of the contacts being independent of the release of the member carrying the resetting press-button, the operation of the cut-

out is ensured even if the press-button is deliberately blocked in the re-setting position;

4. Considerable separation of the contacts, facilitating extinction of the arc when the cut-out operates, the extinction of the arc being further facilitated by blow-out devices varying according to the designed nominal current.

5. The resistance of the device to dead short-circuits consequent upon its high sensitivity which ensures that it operates before heating due to a heavy overload can damage the parts.

6. The possibility of adding a release button which converts the device into a switch-cut-out. This arrangement is particularly valuable for built-in or base-plate installation on account of the very small bulk of the combined switch and cut-out.

7. Finally the very considerable space available for the contacts, permitting multiplication of the points of contact and the accommodation of arc extinguishing means as described above.

What I claim is:

1. An electric cut-out comprising a support, at least one contact piece carried rigidly by said support cooperating movable contact pieces, an at least partly yielding member carrying said movable contact pieces in front of the first contact piece, a transversal blade normally engaging last mentioned contact carrying member and holding it in its operative position, yielding means urging the transversal blade into its operative position, a heat sensitive member carried by the support, a pusher rod movably carried by the support and housing the transversal blade and associated yielding means, a catch and spring system holding the pusher rod in its depressed position in which the transversal blade engages the operative contact carrying member, means whereby the heat sensitive member, when heated, urges the transversal blade carried by the pusher member in depressed position against the action of its associated yielding means into its inoperative position, means whereby the contact carrying member when released with reference to the transversal blade enters its inoperative position and acts on the catch and spring system for releasing the pusher member, a spring urging the pusher member into its outermost position in which the transversal blade carried by said pusher member reengages the contact carrying member in its outer released inoperative position.

2. An electric cut-out comprising a support, at least one contact piece carried rigidly by said support, cooperating movable contact pieces, an at least partly yielding member carrying said movable contact pieces in front of the first contact piece, a transversal blade normally engaging last mentioned contact carrying member and holding it in its operative position, yielding means urging the transversal blade into its operative position, a heat sensitive member carried by the support, a pusher rod movably carried by the support and housing the transversal blade and associated yielding means, a catch and spring system holding the pusher rod in its depressed position in which the transversal blade engages the operative contact carrying member, means whereby the heat sensitive member, when heated, urges the transversal blade carried by the pusher member in depressed position against the action of its associated yielding means into its inoperative position, means whereby the contact carrying member when released with reference to the transversal blade enters its inoperative

position and acts on the catch and spring system for releasing the pusher member, a spring urging the pusher member into its outermost position in which the transversal blade carried by said pusher member reengages the contact carrying member in its outer released inoperative position, a releasing knob, a leverage controlled thereby and adapted to act in the position obtained by depression of the knob on the catch acting on the pusher member in antagonism with the catch spring for releasing the pusher member, the displacement of the pusher member under the action of its spring moving the transversal blade with it and shifting therewith the contact carrying member into its inoperative position.

3. An electric cut-out comprising a support, at least one contact-piece carried rigidly by said support, cooperating movable contact pieces, a further movable contact piece, an at least partly yielding member carrying all said movable contact piece in front of the first contact pieces, a normally stationary carbon contact piece of same polarity as the first mentioned contact piece, means whereby the carbon contact-piece is adapted to continue feeding current to the corresponding movable contact piece during a short period after the breaking of the circuit through the first-mentioned stationary contact piece, a transversal blade normally engaging last mentioned contact carrying member and holding it in its operative position, yielding means urging the transversal blade into its operative position, a heat sensitive member carried by the support, a pusher rod slidably carried by the support and housing the transversal blade and associated yielding means, a catch and spring system holding the pusher rod in its depressed position in which the transversal blade engages the operative contact carrying member, means whereby the heat sensitive member, when heated, urges the transversal blade carried by the pusher member in depressed position against the action of its associated yielding means into its inoperative position, means whereby the contact carrying member when released with reference to the transversal blade enters its inoperative position and acts on the catch and spring system for releasing the pusher member and a spring urging the pusher member into its outermost position in which the transversal blade carried by said pusher member reengages the contact carrying member in its outer released inoperative position.

4. An electric cut-out comprising a support, at least one contact piece carried rigidly by said support, cooperating movable contact pieces, an at least partly yielding member carrying said movable contact pieces in front of the first contact piece, a transversal blade normally engaging last mentioned contact carrying member and holding it in its operative position, yielding means urging the transversal blade into its operative position, a bi-metallic heat sensitive strip member carried by the support, a pusher rod slidably carried by the support and housing the transversal blade and associated yielding means, a catch and spring system holding the pusher rod in its depressed position in which the transversal blade engages the operative contact carrying member, means whereby the heat sensitive member, when heated, urges the transversal blade carried by the pusher member in depressed position against the action of its associated yielding means into its inoperative position, means whereby the contact carrying member

when released with reference to the transversal blade enters its inoperative position and acts on the catch and spring system for releasing the pusher member, a spring urging the pusher member into its outermost position in which the transversal blade carried by said pusher member reengages the contact carrying member in its outer released inoperative position.

5. An electric cut-out comprising a support, at least one contact-piece carried rigidly by said support, cooperating movable contact pieces, a further movable contact-piece, an at least partly yielding member carrying all said movable contact pieces in front of the first contact piece, a normally stationary carbon contact piece of same polarity as the first mentioned contact piece adapted to move between its operative position in which it lies in the plane of the first mentioned stationary contact piece and a current breaking position in which it lies nearer the cooperating further movable contact piece than the first mentioned stationary contact piece with reference to the corresponding movable contact pieces, a spring urging the carbon contact-piece towards the corresponding further movable contact-piece, a transversal blade normally engaging last mentioned contact carrying member and holding it in its operative position, yielding means urging the transversal blade into its operative position, a heat sensitive member carried by the support, a pusher rod slidably carried by the support and housing the transversal blade and associated yielding means, a catch and spring system holding the pusher rod in its depressed position in which the transversal blade engages the operative contact carrying member, means whereby the heat sensitive member, when heated, urges the transversal blade carried by the pusher member in depressed position against the action of its associated yielding means into its inoperative position, means whereby the contact carrying member when released with reference to the transversal blade enters its inoperative position and acts on the catch and spring system for releasing the pusher member and a spring urging the pusher member into its outermost position in which the transversal blade carried by said pusher member reengages the contact carrying member in its outer released inoperative position.
6. An electric cut-out comprising a support, associated rockable rounded contact pieces of same polarity, a pivot rigid with the support for said contact pieces, cooperating movable contact pieces, an at least partly yielding member carrying said movable contact pieces in front of the first contact pieces, springs urging the rockable contact pieces to move round their pivots towards the corresponding movable contact pieces to contact therewith through a substantially large frictional area, a transversal blade normally engaging last mentioned contact carrying member and holding it in its operative position, yielding means urging the transversal blade into its operative position, a heat sensitive member carried by the support, a pusher rod slidably carried by the support and housing the transversal blade and associated yielding means, a catch and spring system holding the pusher rod in its depressed position in which the transversal blade engages the operative contact carrying member, means whereby the heat sensitive member, when heated, urges the transversal blade carried by the pusher member in depressed position against the action of its associated yielding means into its inoperative position, means whereby the contact carrying member

member when released with reference to the transversal blade enters its inoperative position and acts on the catch and spring system for releasing the pusher member, a spring urging the pusher member into its outermost position in which the transversal blade carried by said pusher member reengages the contact carrying member in its outer released inoperative position.

7. An electric cut-out comprising a support, at least one contact piece carried rigidly by said support, cooperating movable contact pieces, an at least partly yielding member carrying said movable contact pieces in front of the first contact piece, a transversal blade normally engaging last mentioned contact carrying member and holding it in its operative position, yielding means urging the transversal blade into its operative position, a heat sensitive member carried by the support, a pusher rod slidably carried by the support and housing the transversal blade and associated yielding means, a catch and spring system holding the pusher rod in its depressed position in which the transversal blade engages the operative contact carrying member, means whereby the heat sensitive member, when heated, urges the transversal blade carried by the pusher member in depressed position against the action of its associated yielding means into its inoperative position, means whereby the contact carrying member when released with reference to the transversal blade enters its inoperative position and acts on the catch and spring system for releasing the pusher member, a spring urging the pusher member into its outermost position in which the transversal blade carried by said pusher member reengages the contact carrying member in its outer released inoperative position, a releasing depressable knob on the support, an antagonistic spring acting on said releasing knob

and mechanical means whereby the depression of the knob urges the transversal blade against the action of the yielding means for releasing the operative contact carrying member.

- 5 8. An electric cut-out comprising a support, at least one contact piece carried rigidly by said support, cooperating movable contact pieces, an at least partly yielding member carrying said movable contact pieces in front of the first contact piece, a transversal blade normally engaging last mentioned contact carrying member and holding it in its operative position, yielding means urging the transversal blade into its operative position, a spirally twisted bi-metallic strip member carried by the frame at one end and the free end of which is adapted to move under the action of heat, a pusher rod slidably carried by the support and housing the transversal blade and associated yielding means, a catch and spring system holding the pusher rod in its depressed position in which the transversal blade engages the operative contact carrying member, means whereby the bi-metallic member, when heated, urges the transversal blade carried by the pusher member 10 in depressed position against the action of its associated yielding means into its inoperative position, means whereby the contact carrying member when released with reference to the transversal blade enters its inoperative position and acts on the catch and spring system for releasing the pusher member, a spring urging the pusher member into its outermost position in which the transversal blade carried by said pusher member reengages the contact carrying member 15 20 25 30 35 in its outer released inoperative position
